UNITED STATES PATENT OFFICE.

HENRY HILLEBRAND, OF BROOKLYN, NEW YORK.

PROTECTIVE LIQUID-DISPENSING SYSTEM.

1,170,907.

Specification of Letters Patent.

Patented Feb. 8, 1916.

Application filed November 16, 1914. Serial No. 872,414.

To all whom it may concern:

Be it known that I, HENRY HILLEBRAND, a citizen of the United States, residing at Brooklyn, in the county of Kings and State 5 of New York, have invented certain new and useful Improvements in Protective Liquid-Dispensing Systems; and I do hereby declare the following to be a full, clear, and exact description of the invention, such as 10 will enable others skilled in the art to which it appertains to make and use the same.

This invention relates to an advertising apparatus and more particularly to a construction whereby the manipulation of a 15 faucet or the like for dispensing a liquid, causes said advertising medium to come into use.

It has for an object to provide an advertising medium whereby manipulation of 20 a faucet displays the advertisement.

A further object of this invention is to provide a checking means for recording the number of times the faucet is actuated.

A further object of this invention is to 25 provide a protection to the purchaser by assuring him that he obtains the beverage called for, by forming a display, as well as forming an electric circuit which includes an attachment upon the genuine container for the liquid to be dispensed.

A further object of this invention is a provision for an attachment for a standard faucet whereby partial rotation of the stem thereof, closes an electric circuit to actuate 35 a recording and display mechanism.

A further object of this invention is a provision of a tube by which the container of a beverage is connected to a faucet, this tubing having an electrical conductor formed 40 therein and said tubing with the inclosed conductor forming a circuit for an electric current to prevent malicious tampering with said tubing or the connections between the container and the faucet.

A further object of this invention is a provision of a circuit closing switch actuated by the stem of a faucet and a time controlled circuit closer actuated by the switch carried by the stem of the faucet.

A further object of this invention is a provision of a switch actuated by the stem of a faucet to include a low voltage circuit, a relay included in said low voltage circuit, and a circuit closure for a high voltage circuit, 55 actuated by said relay.

Further objects will be apparent from the

following specification, appended claims and drawings in which—

Figure 1 shows an isometric perspective view of a liquid dispensing unit showing the 60 elements of this invention applied thereto, Fig. 2 is a vertical sectional view through a faucet having a switch applied thereto, Fig. 3 is a horizontal sectional view as on the line 3—3 of Fig. 2, Fig. 4 is a perspective view of 65 a section of tubing, Fig. 5 is a cross sectional view as on the line 5—5 of Fig. 1 and Fig. 6 is a sectional view of a time controlled circuit closing device.

This invention is intended for use in any 70 instance where liquids are being dispensed and it combines a checking system with an advertising medium in such a manner as to enable the purchaser being assured that he is obtaining the beverage asked for. By the 75 arrangement of the parts to be hereinafter described, it is clearly seen that it would be impossible for a dealer to substitute an inferior product to the one having a demand and by the use of a checking system, it is 80 easy for the producer to ascertain the exact number of sales of the retailer.

Referring to the drawings in which similar reference numerals indicate similar parts throughout the several views, there is shown 85 a counter 10 having the usual faucets 11, 12 and 13 projecting therefrom for convenient access to the dispenser, and these faucets may be connected to the tubes 14, 15 and 16 in which coils 17 may be formed in a cooling chamber 18. It occurs that in most places where beverages are dispensed, regular brands of beverages are handled and for which there is no need of any special advertising, but along with these regular 95 brands may be a special brand of a superior quality having a special demand and in this case, it will be assumed that the faucet 11 is intended to dispense the special brand of liquid and this faucet is connected as 100 through the tubing 14 to the container 19, while the tubing 15 and 16 connect with the containers 20 and 21. The tubing 14 is more clearly shown in Fig. 4 of the drawings and passing through said tube in a concealed manner is an electrical conductor 105 22. This conductor may be formed in the wall of said tube as shown, or with the proper covering it may pass through the interior of the tube 14. At a desired point, 110 the conductor 22 leaves the tube 14 and passes to a terminal, to be hereinafter de-

scribed, at one end of the tube, while at the opposite end of the tube this conductor passes through the wall of the tube 14 and extends to a block 23 which may be permanently attached to the container 19 and the block 23 is also electrically connected to the tube 14 as shown, so that a circuit is formed which includes the tube 14 and the insulated conductor 22. This arrangement of parts

- 10 prevents a dealer from maliciously connecting a counterfeit container to the faucet 11 as to break any portion of the tube 14 would open the circuit and render parts to be described, inoperative. The several containers, 19, 20 and 21 may have connection with an air line 24, as shown, by which pressure may be applied to the containers to enable dispensing the contents thereof.

The faucet 11 has its stem 25 provided 20 with a pin 26 which extends in the path of the contacts 27 so that as said stem is partially rotated, the pin 26 closes the circuit between said stem and the insulated contact. As the faucet is connected with the tube 14, 25 the stem 25 forms part of the circuit and it is clearly seen that as the stem 25 is rotated as in dispensing the liquid, the circuit is closed between the pin 26 and the contact 27 from where a conductor 28 passes through 30 a small tube 29 which may be soldered or brazed to the faucet as shown, which leads to any desired point from where the conductor 28 may pass to a terminal 30. The tube 29 being positively secured to the faucet 11, 35 protects the conductor 28 when said faucet and piping are being cleaned and it also prevents tampering with the system. The conductor 22 leads to the terminal 31 which with the terminal 30 form the ends of the 40 electric circuit which includes the piping and faucet.

From the terminal 30, the conductor 28 leads to an electromagnet 32 which is intended to actuate a recording mechanism 45 33 and from said electromagnet, the circuit continues through the conductor 34 to the electromagnet 35 of a relay from where it continues as through the conductor 36 through the double pole switch 37 to the battery 38. The conductor 22 includes one of 50 the members of the switch 37 and leads to the opposite terminal of the battery 38.

When the magnets 35 are energized, the armature 39 is attracted and in its movement it closes a circuit between the contacts 40 at which time the winding 41 of solenoid is energized in having the circuit completed through the wires 42 and 43 which are bridged across the wires 44 and 45 which lead from any source of electrical supply of voltage common to electric lighting circuits. When the winding 41 is energized, the core of the solenoid is raised, at which time the cam 47 is rotated to cause the contacts 48 to close the circuit which includes the wires 49

and 50 and the electric lights 51. The solenoid is arranged to have its core slide within the winding 41 upon closing the circuit through said winding, but said core has a retarded return stroke which is produced by 70 having said core expel the air from a dash pot as through a valve 53 and to allow said core to fall in a retarded stroke by the proportionate admission of air into the cylinder 54 as through the bleed hole 55. 75

The operation of this device is apparent from the foregoing, but as a brief explanation of the operation, it may be assumed that a dispenser intends to draw a glass of beverage from the container 19, in turning 80 the stem of the faucet 11, the circuit is closed through the batteries 38, winding 32 and windings 35, at which time a record is made by the apparatus 33 as on a tape and the high voltage circuit through the winding 85 31 is closed. The circuit through the lamps 51 is then closed by the action of the solenoid and the lamps 51 remain lighted until the core 46 resumes its normal position. The stem of the faucet 11 may be rotated from 90 its normal position for only a brief period but the action of the solenoid 41 may be adjusted to allow the lights 51 to remain lighted for any desired length of time. The lights 51 will be placed in a frame in which 95 a transparent or translucent advertisement 52 is placed so that upon illumination, as by the lights 51, the advertisement becomes conspicuous.

Various modifications may be made within the scope of this invention without departing from the spirit thereof, and it is also apparent that the system may be duplicated, if so desired, or with the slight modifications it may be adapted for use in 100 dispensing any particular line of materials.

Having thus described my invention, I claim:—

1. In a system for dispensing liquids, in combination with a valve controlled outlet from a container, an electric switch actuated by the stem of said valve, a source of electrical supply for said electrical switch, a high voltage relay in circuit with said switch and source of electrical supply, and a time controlled illumination display actuated by said relay. 11

2. In a system for dispensing liquids, in combination with a valve controlled outlet from a container, an electric switch actuated by the stem of said valve, a source of electrical supply for said switch, an electrical recording mechanism and a high voltage relay in circuit with said source of electrical supply and said electric switch and an illuminated display actuated by said relay. 12

3. In a system for dispensing liquids, in combination with a valve controlled outlet from a container, a metallic tube between 13

- said valve and said container, an insulated conductor formed in said tube, a circuit closer carried by said container, a switch actuated by the stem of said valve, an electrically controlled recording mechanism, a source of electrical supply and said switch actuated by said valve stem closing the circuit through the recording mechanism source of supply and including the tube and insulated conductor in said tube.
4. In a system for dispensing liquids, a valve controlled outlet from a container, having the container at a remote point from said valve, an electric switch actuated by said valve stem, an electrically actuated recording mechanism in a circuit with said switch, a source of electrical supply in said circuit, said tube being in said circuit, an insulated conductor formed in said tube, and a circuit closing attachment carried by said container to complete the circuit through the source of supply, recording mechanism tube and insulated conductor formed in said tube.
5. In a system for dispensing liquids, in combination with a container, and a valve controlled outlet at a remote point, a connecting tube comprising a metallic tube having a passage formed therein for fluid and an insulated electrical conductor embedded therein.
6. In a system for dispensing liquids comprising in combination a valve controlled outlet from a container, an electric circuit closer actuated by said valve, a source of low potential electrical supply, for said circuit closer, a relay actuated by said low potential circuit closer, a source of high potential electrical supply, a circuit closer for said high potential current, a time controlled restoring element for said high potential circuit closer, said relay closing the circuit through said timing element having an indefinite duration, said time controlled circuit closer having a predetermined interval of operation, and a display actuated by said time controlled circuit closer.
- In testimony whereof I affix my signature in presence of two witnesses.

HENRY HILLEBRAND.
